UNITED STATES PATENT OFFICE.

HERBERT K. TABLER, OF COLMAR, ILLINOIS.

GATE.

Application filed March 31, 1928. Serial No. 266,322.

This invention relates to gates and more particularly to farm gates.

One of the primary objects of the present invention is to provide a farm gate which is not only movable in a horizontal plane but which is adjustable at one end in a vertical plane whereby the entrance and exit of different sizes of stock can be readily controlled from an enclosure.

10 Another object of the invention is the provision of a gate embodying longitudinal bars connected through the medium of suitable pivot pins with vertical bars whereby the longitudinal bars will be permitted to swing 15 in a vertical plane with means normally tending to lift the gate at its outer end.

A further object of the invention is the provision of a latch carried by the gate for engaging in keeper recesses a gate post 20 for holding the gate in different elevated, adjusted positions against the tension of said spring means to permit the entrance or exit of different sized stock from an enclosure.

25 A further object of the invention is the provision of an adjustable stop carried by the gate for limiting the swinging movement of the spring-controlled means for causing the elevating of the gate, whereby the swinging movement of the gate can be limited.

A further object of the invention is the provision of means for engaging the lower free end of the gate to limit the swinging movement of the gate in a horizontal plane.

35 A still further object of the invention is to provide an improved farm gate of the above character, which will be durable and efficient in use, one that will be simple and easy to manufacture, and one which can be placed upon the market at a reasonable cost.

40 With these and other objects in view, the invention consists in the novel construction, arrangement and formation of parts, as will be hereinafter more specifically described, 45 claimed and illustrated in the accompanying drawing, in which drawing:

Figure 1 is a side elevation of the improved gate.

Figure 2 is a top plan view of the improved gate,

Figure 3 is a vertical sectional view through the gate taken on the line 3-3 of Figure 1, looking in the direction of the arrows,

55 Figure 4 is an enlarged detailed sectional view illustrating the means of connecting

the lifting spring with one of the vertical members of the gate,

Figure 5 is an enlarged detailed sectional view illustrating the means of connecting 60 the gate with the swinging, elevating lever of the gate,

Figure 6 is a side elevation of a slightly modified form of gate,

Figure 7 is an enlarged fragmentary vertical section taken on the line 7-7 of Figure 6 looking in the direction of the arrows, illustrating the form of stop for the elevating lever used in that form of the gate shown in Figure 6,

Figure 8 is a detailed vertical section taken on the line 8-8 of Figure 6, looking in the direction of the arrows illustrating the holding bracket for the lower free end of the gate,

Figure 9 is an enlarged vertical section taken on the line 9-9 of Figure 1 looking in the direction of the arrows, illustrating the form of stop for the swinging elevating lever used in that form of the invention 80 shown in Figure 1, and

Figure 10 is a fragmentary side elevation of one of the longitudinal rails of the gate illustrating a method of reinforcing the terminals of the rail.

Referring to the drawings in detail, wherein similar reference characters designate corresponding parts throughout the several views, the letter A generally indicates one form of my improved gate which comprises a plurality of longitudinally extending rails 15 connected together by end vertical bars 16 and 17 and intermediate bars 18.

The longitudinal and vertical rails 16, 17 and 18 are connected together through the 95 medium of suitable pivot pins and slots 19, whereby the gate is flexible in its nature, in that the same can be moved up and down in a vertical plane.

The inner edge of the gate is connected by 100 any preferred type of hinges 20 with a supporting gate post 21.

The opposite end of the gate carries a sliding latch 22 which is preferably inclined downwardly as shown in Figure 1 of the drawing. This sliding latch 22 is supported by anti-friction rollers 23 and 24 which can be supported respectively by brackets 25 and the vertical front rails 17. The sliding latch 22 is adapted to fit in any one of a plurality 110 of keeper recesses 26 which can be formed in the inner face of the fence post 27. It is to

be noted that these recesses are arranged in vertical alignment and by placing the latch in different keeper recesses, the gate can be maintained in different vertical adjustments so that different sized stock can go under the gate without letting stock of a different size through the gate.

I provide novel means for elevating the gate upon the release of the latch 22 and this means comprises a gate elevating lever 28 which is disposed in relatively close proximity to the rear vertical upright 16 of the gate. In the present instance, the elevating lever 28 embodies channel bars 29 and 30 disposed on opposite sides of the gate and these bars are pivotally connected at their lower ends to one of the longitudinal rails 15 by means of a pivot pin 31.

The levers or bars 29 and 30 are also connected together by cross pins 32 at a point intermediate to the ends thereof. As clearly shown in Figure 2 of the drawing, the upper ends of the bars 29 and 30 are flared outwardly in opposite directions and are connected together by cross pins 33. These ends of the bars 29 and 30 have rings or eyes 34 connected thereto and these eyes or rings, in turn, have attached thereto terminals of a pull cable 35. The intermediate portion of this pull cable is trained about a pivoted pulley 36, which is connected to the outermost intermediate pair of vertical uprights 18. A relatively heavy contractile coil spring 37 is provided for normally maintaining a pull on the lever 28 so that when the latch is released, the lever will act to automatically raise the outer end of the gate. The outer end of the contractile coil spring 37 is provided with a hook 38, the bill of which can be hooked over the intermediate cross pin 32 carried by the lever 28. The opposite end of the spring is connected to the gate A through the medium of a link 39 which is secured to the gate and a chain 39^a which is connected to an end of the link and to which said end of the spring is connected. The link 39 is positioned between the bars 16 of the gate A and it is provided with a plurality of spaced openings 40. It is secured in place by a pin 41 which removably passes through the bars 16 and one of the openings 40. The spring 37 is placed under the approximately required tension by engaging it with one of the links of the chain 39^a and the final tensioning of the spring is effected by adjusting the link 39 longitudinally with respect to the gate A. The provision of the link 39 with the openings 40 permits this adjustment of the link and it may be easily adjusted and the tension of the spring easily regulated by raising the free end of the gate high enough to slacken the chain 39^a.

It is to be also noted at this point that

the swinging pulley 36 can also be raised 65 and lowered on the outermost pair of vertical uprights 18 so that the pull on the gate can also be adjusted.

In view of the fact that the intermediate portion of the cable 35 is trained about the 70 pulley, the cable will form an equal pull on each side of the gate.

A U-shaped holding bracket or stirrup 42 is provided on the extreme lower outer end of the gate and when the gate is in its lowered position, the same rests in the U-shaped bracket or stirrup and is thus held against swinging movement in a horizontal plane.

From the description so far, it can be seen that a novel gate has been provided which 80 is not only permitted movement in a horizontal plane but is also permitted movement in a vertical plane. Not only will a gate of this character be found to be of advantage in stock farms but can also be used to advantage in uneven or sloping ground, in that, upon release of the gate, the gate will automatically elevate itself above the ground level. The swinging movement of the elevating lever 28 can be limited so that the gate will only raise a predetermined distance upon the release of the latch 22. This means embodies a stop, shown in detail in Figure 9 of the drawing. The stop includes a sliding U-shaped bracket 50 carried by the 95 top longitudinal rail 15 and this sliding U-shaped bracket 50 is provided with downwardly extending stop ears 51 disposed in the path of the lifting lever 28.

In order to hold the stop bracket in different adjusted positions an L-shaped holding pin 52 is provided. This pin 52 is inserted through the bracket 50 and any one of a plurality of openings 53 formed in the top longitudinal rail 15. To prevent the pin from being accidentally displaced, the upper end thereof is formed with an eye 54 which carries a short length of chain 55. This chain can be swung over the top rail of the gate and one link thereof can be moved over the free end of the L-shaped pin extending through the bracket.

The gate can be made of any desired material and in Figures 1 to 3 inclusive, I have shown the longitudinal rails made of wood but, I prefer that the gate be made of other material and in Figures 6 to 8 inclusive, I have shown a gate indicated generally by the reference character B constructed of iron or steel tubing. The gate B embodies upper and lower longitudinally extending rails 60 and 61 which are pivotally connected by means of pivot pins 62 with end uprights 63 and 64. An intermediate pair of uprights 65 is also provided and these uprights are pivotally connected to the upper and lower longitudinally extending rails by means of pivot pins and brackets 66.

The upright 63 is connected to a supporting gate post 64 by the use of suitable hinges 66.

The gate post 67 is provided with a plurality of inclined keeper recesses 68 any one of which is adapted to fit the sliding latch 69. This latch can include a rod 70 connected to a piece of tubing 71 and the inner end of the rod 70 can have attached thereto a suitable operating handle 72. Anti-friction guide 73 can be carried by one of the intermediate uprights 65 and by the end upright 64.

It is to be noted that in this form of the gate, the same can be swung in a vertical plane in view of the fact that the longitudinal rails 60 and 61 are pivotally connected to the innermost upright 63.

A seat 74 is provided for the lower outermost end of the gate and this seat can be constructed in any desired way such as by the use of spaced strap iron strips 74 connected by cross pins 75. This prevents swinging movement of the gate in a horizontal plane when the lowermost longitudinal rail 61 fits in said seat.

This gate is also adapted to be automatically raised and lowered upon movement of the latch 69 out of engagement with the keeper recess 68 and this means also includes the elevating lever 76. This lever has its lower end pivotally connected as at 77 to the innermost intermediate upright 65. The upper end of the elevating lever 76 is connected through the medium of a cable 78 with the outermost intermediate upright 65 adjacent to the lower end thereof. This cable 78 has its intermediate portion trained over a swinging pulley 79 which also can be raised and lowered on the intermediate upright. The terminals of the cable are connected to the upper end of the elevating lever 76. This lever is normally drawn toward the pivot point of the gate by means of the relatively heavy contractile coil spring 80, which is connected respectively to the elevating lever 76 and the upper end of the upright 63.

A stop is also provided for the elevating lever 76 in this form and this stop, indicated by the reference character 81, includes an open cuff 82 which is adapted to be swung about the upper rail 60. Ears 83 are formed on the cuff and a pin 84 extends through the said ears and can be provided with stop sleeves 85 against which the lever is adapted to bear when the latch is released. This stop 81 can be moved to different positions on the rail 60 in order to limit the swinging movement of the elevating lever.

If preferred, when the gate is made of wood, the ends of the longitudinal rails can be reinforced so as to prevent splitting thereof and, in Figure 10 of the drawing, I have shown the end of the one rail 15 wrapped

with wire, as indicated by the reference character 86.

It will be obvious from the foregoing that a novel farm gate has been provided, which is susceptible for a number of different uses in view of the fact that the same swings both in a vertical and a horizontal plane.

Changes in details may be made without departing from the spirit or the scope of this invention, but:

What I claim as new is:

1. The combination with a pair of spaced fence posts, of a gate including a pair of uprights, means hingedly connecting the innermost uprights to one of the fence posts, longitudinal rails hingedly connected to the uprights, a lifting lever pivotally connected at its lower end adjacent to the inner end of said gate, resilient means normally tending to move the lifting lever toward the inner end of the gate, means connecting the lever adjacent to its upper end with the gate adjacent to the outer end thereof, and an adjustable stop for limiting the swinging movement of the lever in one direction. 90

2. The combination with a pair of spaced fence posts, of a gate including inner and outer uprights, means hingedly connecting the inner upright to one fence post, longitudinally extending rails, means pivotally connecting the rails to the uprights, a swinging elevating lever pivotally connected at its lower end adjacent to the inner end of the gate and to said gate, a contractile coil spring normally tending to move the lever toward the inner upright, means for adjusting the tension of said spring, means connecting the gate adjacent to its outer end with a lever adjacent to the upper end thereof, and a sliding latch adapted to engage in any one of a plurality of keeper recesses formed in the other gate post. 100

3. The combination with a pair of spaced gate posts, of a gate including inner and outer uprights, longitudinally extending rails hingedly connected to said uprights, means swingably connecting the inner upright to one fence post, a swinging elevating lever hingedly connected at its lower end to the gate adjacent to the inner end thereof, a contractile coil spring normally tending to move the lever toward the inner upright, a swinging pulley carried by the gate adjacent to the outer end thereof, a cable trained about said pulley, and means connecting the inner end of said cable to the lever adjacent to the upper end thereof. 110

4. The combination with a pair of spaced fence posts, of a gate including inner and outer uprights, longitudinally extending rails pivotally connected to said uprights, means hingedly connecting the inner upright to one fence post, a swinging elevating lever carried by the gate adjacent to the inner end thereof, a contractile coil spring nor- 125

5 mally tending to move the lever toward the inner vertical upright, a member connected to the lever and to the gate outwardly beyond the lever, and a stop adjustably supported by the uppermost longitudinal rail and arranged in the path of the swinging elevating lever.

10 5. A gate comprising uprights, rails pivoted to the uprights, a lever pivoted at one end to one of the rails, a member connected to the lever and to one of the uprights, a member adjustably connected to another of the uprights, and a spring connected to the lever and said last named member.

15 6. A gate comprising uprights, rails pivoted to the uprights, a lever pivoted at one end to one of the rails, a member connected to the free end of the lever and to one of the uprights, a member adjustably connected to another of the uprights, a chain connected

20 to said last named member, and a spring connected to the lever between the ends of the latter and connected to the chain.

25 7. In combination, a gate having pivotally connected uprights and rails, a lever pivoted at one end to the gate, a spring connected to the lever and to the gate, and a member connected to the lever and to the gate, the spring and member extending from opposite sides of the lever.

30 8. In combination, a gate having pivotally connected uprights and rails, a lever pivoted at one end to the gate, a spring connected to the gate and to the lever between the ends of the latter, and a member connected to the gate and to the lever outwardly beyond the point of connection of the spring therewith.

35 In testimony whereof I affix my signature.

HERBERT K. TABLER.
